[57] **ABSTRACT**

Electromagnetic relay comprising a fixed magnetic circuit and a movable armature for switching pairs of movable conductors. The movable conductors and the armature are installed inside the casing supporting the excitation winding at one end thereof and the release of the armature is provided by the spring portion of the movable conductors which are made in the shape of elastically flexible wires and are secured with this armature.

MINIATURE ELECTROMAGNETIC RELAY

The present invention relates to a miniature electromagnetic relay suitable for being mounted particularly on a map of printed circuits.

For this purpose, it is desirable to provide a relay which has small overall dimensions, is light and can be easily attached to or provided on a map of printed circuits either by plugging or soldering. It is further required that a relay of this type be sturdy and very reliable, while having a low power consumption. Lastly, a low cost of manufacture is an indispensable condition for large-scale industrial distribution thereof.

The present invention is directed to a miniature relay of the type referred to above which comprises several "rest-work" (R-T) contacts—in principle as many as may be required for the specific circuit involved and wherein a low cost of manufacture is assured by virtue of the elimination of any piece or element that might require machining, or high-precision manufacture. This is accomplished by the use of a small number of pieces or elements to form a switch capable of simple installation as well as simple regulation or control.

It is known that in a switch of the type of which the invention is directed, an R-T contact is provided which comprises a central element called a "common" contact and which, in the absence of excitation or energization of the relay, bears on a fixed so-called "rest" contact. With the energization of the relay, due to the attraction of the magnetic circuit the common contact will come to bear or act on another fixed contact, a so-called work contact.

The existing problem as stated above is solved, in accordance with the present invention, by providing a switch having a common contact consisting of a structure having an elongated shape, for example, a wire, rod or homogeneous resilient metallic bar. This common contact has a constant cross-section over the entire length thereof, comprising in an end region or area an anchored portion having an extremity serving as a connection on one side while the other extremity is divided successively into a first zone of elastic deformation, a second zone which is integral with a magnetic armature, a third zone also providing elastic deformation, and lastly, an extremity serving as the contact portion of the "common" contact. The aforementioned armature, which is made from soft magnetic metal, is connected with the structure of the common contact by means of an insulating body. The vane is placed opposite an opening in a C-shaped magnetic circuit which in operative connection with an excitation coil.

In the non-energized condition, the contact portion of the elastic structure bears upon or is supported against the rest contact due to the effect of its elastic tension. When the coil is excited, the attraction of the vane by the magnetic circuit results in the shifting of the common contact to the working contact. When the current is suppressed in the coil, the elasticity of the structure resets or returns the common contact to the rest contact.

It is an object of the present invention to provide a relay which eliminates or otherwise avoids the disadvantages inherent in known devices of a similar type.

It is another object of the present invention to provide a relay which is made up of a minimum number of elements.

It is a further object of the present invention to provide a relay which is relatively simple to install and control in operation.

It is a further object of the present invention to provide an electromagnetic relay having a magnetic circuit which need not have an annular configuration to properly operate the relay contacts.

It is still a further object of the present invention to provide a relay which is small in size and lightweight, but sturdy and reliable in operation.

It is still another object of the present invention to provide a relay which has contacts of a noble metal, but is economical to manufacture.

These and other objects, features and advantages of the present invention will become more apparent from the following detailed description when taken in conjunction with the accompanying drawings, wherein:

FIG. 1 illustrates schematically the basic elements of the present invention;

FIG. 2 is a side sectional view of one embodiment of the relay proposed by the present invention;

FIG. 3 is a sectional view taken along line II-II of FIG. 2; and

FIG. 4 is an exploded perspective view of a portion of the disclosed relay.

As seen in FIG. 1, a resilient elongated metallic structure A forms a common contact cross-section and the following operative zones: a, a first extremity serving as a connection portion for contact with an exterior circuit (not shown); b, an anchoring zone wherein the contact is supported by an insulating piece 28; c, a first zone of elastic deformation; d, a zone which is connected with a armature 18 made from soft magnetic material by means of an insulating body 20; e, a second zone of elastic deformation; and f, a second extremity serving as the contact portion of the common contact. The two fixed contacts have been designated, respectively, with reference symbols g (rest contact) and h (working contact).

The metallic vane 18 is placed adjacent the opening of a C-shaped magnetic circuit of which only the branches 14 and 16 have been shown in FIG. 1. As is well known in the art, the branches 14 and 18 close on a yoke and the magnetic circuit may be subjected to the field of an induction coil (which have not been shown in FIG. 1).

In one embodiment of the present invention, illustrated in FIGS. 2 and 3, the relay is mounted in a casing 2, made for example, from hard plastic material, and comprising a tube 4 having a rectangular cross-section, having at the ends thereof flanges 6 and 8 being disposed at the respective ends thereof. Placed around the tube 4 between the flanges 6 and 8 is a winding 10 of an enameled copper wire for example.

A magnetic circuit comprises a yoke 12 forming a bridge between the edges of the flanges 6 and 8 on one side of the casing 2, a lower L-shaped branch 14 covering the portion of the flange 6 adjacent the yoke 12 and extending inside of the tube 4 through the bottom, an upper L-shaped branch 16 covering the portion of the flange 8 adjacent the yoke 12 and extending into the tube 4 from above. The yoke 12 engages in channels in the flanges 6 and 8, as is apparent from FIG. 3. For purposes of the installation, this magnetic circuit will consist of at least two parts which may be assembled, for

example, by gluing or any other simple equivalent fastening process. The magnetic circuit elements 12, 14, and 16 consist advantageously of an alloy such as Anhyster or the like.

Adjacent the opening between the branches 14 and 16 of the magnetic circuit is a armature 18 made from a magnetic alloy which is connected, by means of a small insulating block 20, with a group of pairs of parallel wires 22 made of a resilient conductive alloy. A certain portion of these pairs of wires 22 is embedded or anchored in an insulating support 24 consisting, for example, of an organic polymer of the polyamide type or group, or the like. The insulating support 24 comprises an elongated block 26 which occupies the entire length of the tube 4 on the side opposite the magnetic circuit, and a short block 28 which serves to retain the lower branch 14 of the magnetic circuit and the pairs of wires 22. These two blocks 26 and 28 may be interconnected by any known means, such as gluing, screwing, or merely the forcible engagement in the tube 4.

The tow parallel wires 22 of each pair constitute or make up the contact structure having the elongated form A as described in connection with FIG. 1. The lower portion of the wires 22 passing or extending below the flange serves for the exterior connections to the relay, such as a sleeve (zone a in FIG. 1), and above this portion is the anchoring zone b. The central portion is connected with the magnetic armature 18 (zone d) by means of the insulating block 20. Situated between the block 20 and the anchoring zone is the zone of elastic deformation c. Above the block 20 is a second zone of elastic deformation e, and the extreme end portion of the wires 22 constitutes the contact portion of the common contact (zone f).

The fixed (rest-work) contacts are advantageously connected to or formed of two conductors 30 and 32 embedded in the body of the block 26 with the exclusion of the lower portion which passes below the flange 6 and of the upper portion which has a contact surface to the right of the upper end of the common contacts 22. It is particularly advantageous to employ as conductors 30 and 32 wires that are identical to the wires 22. In the preferred case, the upper end of the wires 30 and 32 is bent back first into the vertical plane and second into the horizontal plane, as is apparent from FIG. 2. The different rest-work contacts of the same relay are separated from each other by means of connecting pieces or sleeves, such as projections 34 in the block 26.

As seen in FIG. 2, at the upper portion of the relay is a lid 36 which is transparent and forms a magnifying glass. This lid is forcibly secured within the tube 4 by means of legs 38 and 40 shown in cross-section in FIG. 3. This lid may consist of methyl methacrylate or the like. The magnifying glass renders it possible to clearly see the contact zones of the fixed and movable conductors, whereby the good operation of the relay is assured.

It is preferable, but not essential, to use two wires 22 instead of a single wire in order to increase the reliability of the contacts, in accordance with current practice for relays specifically designed for the telephone industry.

The wires 22 are advantageously made of a eutectic alloy of silver and copper in a weight ratio of about

72/28. The fixed wires 30 and 32 may consist of the same alloy. One thereby obtains a relay with contacts made from a noble metal.

The rear portion of the insulating block 20 opposite the magnetic circuit 14-16 is shaped to provide for a throttling of air with the face of the contact changes over from the working condition to the condition of rest.

The relay has been illustrated herein with four rest-work contacts, but it is understood that this number of contacts has been indicated solely by way of example and is not intended to be limitative in any way. It is quite possible to either increase or decrease the number disclosed herein by increasing the size of the casing.

It should be noted that, in the relay proposed by the present invention, the magnetic circuit does not require an opening, nor machining of any kind.

FIG. 4 shows an exploded view of the group of elements consisting of the common and fixed contacts of the relay according to the present invention. Also evident from this figure are the four pairs of wires 22 held in position by the block 20, which is made from insulating material and which in turn supports the magnetic armature 18.

The support 26 contains four pairs of wires 30 and 32 whose ends project or extend on one side from the support, the other ends of which are bent back twice in the manner already described. Projections 34 hold the upper ends of the wires 30-32 and separate the contacts of the relay from each other.

While I have shown and described one embodiment in accordance with the present invention, it is understood that the same is not limited thereto but is susceptible of numerous changes and modifications as known to a person skilled in the art, and I therefore do not wish to be limited to the details shown and described herein but intend to cover all such changes and modifications as are obvious to one of ordinary skill in the art.

What is claimed is:

1. A miniature electromagnetic relay comprising a plurality of fixed rest contacts and work contacts, an elongated frame of insulating material having a rectangular cross-section on which there is wound at least one winding, a C-shaped magnetic circuit surrounding said winding on one side of said rectangular frame and having a gap disposed inside of said frame, at least one common elastically flexible wire contact having an elongated shape and constant cross-section, support means for supporting one end of said common contact in cantilever fashion inside said frame adjacent one end of said frame with said one end of said common contact extending out of said frame as a connection portion, a magnetic armature insulatingly secured solely to said common contact at a point substantially midway between said support means and the other free end of said common contact inside said frame, said magnetic armature being disposed adjacent the gap in said magnetic circuit and the other free end of said common contact being disposed between at least one rest contact and one work contact.

2. A relay as defined in claim 1, wherein said common contact is provided in the form of a pair of parallel wires.

3. A relay as defined in claim 2, wherein the wires forming said common contact are made from a silver-copper alloy in a weight ratio of about 72/28.

4. A relay as defined in claim 1, wherein said fixed rest contacts and said fixed work contacts each are formed by a wire extending substantially parallel to said common contact on the same side thereof and having a double bend at the end thereof adjacent the free end of said common contact inside said frame, while the other end thereof extends out of said frame to serve as a connection portion.

5. A relay as defined in claim 4, wherein said support means includes an elongated insulating block disposed inside said frame on the side thereof opposite said magnetic circuit and having said fixed rest and work contacts embedded therein, and another insulating block closing the end of said frame through which said common contact extends and supporting said common contact for movement within said frame.

6. A relay as defined in claim 5, wherein a plurality of 20

common contacts are supported by said support means within said frame.

7. A relay as defined in claim 6, wherein each of said common contacts is provided in the form of a pair of 5 parallel wires.

8. A relay as defined in claim 7, wherein the wires forming said common contact are made from a silver-copper alloy in a weight ratio of about 72/28.

9. A relay as defined in claim 8, wherein said fixed 10 rest contacts and said fixed work contacts each are formed by a wire extending substantially parallel to said common contact on the same side thereof and having a double bend at the end thereof adjacent the free end of said common contact inside said frame, while the other 15 end thereof extends out of said frame

10. A relay as defined in claim 9, wherein a cover member is provided on the end of said frame opposite said support means in the form of a transparent magnifying glass.
